UNITED STATES PATENT OFFICE

LEONARD TOKARSKI, OF HARVEY, ILLINOIS.

DESIGN FOR A KITCHEN CABINET.

61,074.

Specification for Design. Patented June 13, 1922.

Application filed May 16, 1921. Serial No. 469,998. Term of patent 7 years.

To all whom it may concern:

Be it known that I, LEONARD TOKARSKI, a citizen of Poland, residing at Harvey, in the county of Cook and State of Illinois, have invented a new, original, and ornamental Design for a Kitchen Cabinet, of which the following is a specification, reference being had to the accompanying drawing, forming part thereof.

The figure is a view in perspective of a kitchen cabinet, showing my new design.

I claim:

The ornamental design for a kitchen cabinet, as shown.

LEONARD TOKARSKI.
